ISRAEL C. MAYO, OF GLOUCESTER, MASSACHUSETTS.

Design No. 4,153, dated June 14, 1870.

DESIGN FOR A TRANSPARENT SHIELD.

The Schedule referred to in these Letters Patent and making part of the same.

To all persons to whom these presents may come:

Be it known that I, ISRAEL C. MAYO, of Gloucester, of the county of Essex and State of Massachusetts, have invented a new, useful, and ornamental Design for a Transparent Shield for the Burner of a Lantern; and do hereby declare the same to be fully described as follows, and represented in the accompanying drawing, of which—

Figure 1 is a side elevation,

Figure 2, a top view, and

Figure 3, a vertical and transverse section of the said shield.

The shield is to be made of glass, and to constitute a part of the body of a lantern, that is to say, that portion of it which encompasses the burner, and serves to transmit therefrom through such body the rays of light from the flame of the wick.

Furthermore, the shield is to protect the flame from wind and from accidental contact with any article.

In carrying out the design, the bore *a* of the shield is to be cylindrical or slightly conical or tapering.

The shield should terminate at each end with a projecting lip, *b*, or *b'*, which should go entirely around it.

Between each of these lips the outer surface of the shield is to be convex, as shown at *c c*, and the convexity should be continued entirely around the shield. Thus the shield on its outer surface will be circular in horizontal section, but convex entirely around it between the two lips, causing the shield to be thicker in the middle than at its ends, and, as a consequence, it will be very strong and not liable to be easily broken.

The convexity of the shield causes it to refract the light to greater advantage than would be the case were it cylindrical and provided with a series of separate convexities.

I claim the above described new design for a lantern-burner shield.

ISRAEL C. MAYO.
